UNITED STATES PATENT OFFICE.

PHILIP FABER, OF BROOKLYN, NEW YORK, ASSIGNOR TO LENA BILLET, OF BROOKLYN,
NEW YORK.

AMUSEMENT DEVICE.

1,367,868.

Specification of Letters Patent.

Patented Feb. 8, 1921.

Application filed December 9, 1919. Serial No. 343,589.

To all whom it may concern:

Be it known that I, PHILIP FABER, a citizen of the United States, residing in the borough of Brooklyn of the city of New York, in the State of New York, have invented certain new and useful Improvements in Amusement Devices, of which the following is a specification, reference being had to the accompanying drawings, forming a part 10 hereof.

This invention relates to an amusement device of the character in which there is combined competitive sport with healthy exercise. In accordance with the invention there 15 are employed a series of two or more bicycles set on stationary frames and connected operatively through a positive mechanical transmission with a series of visual indicating devices, both of a mechanical and electrical character, which will serve to indicate at all times the relative proficiency of the participants as bicycle riders, and announce the real winner at the conclusion of the race. The principal object of the invention is to provide in an amusement device 20 of this character athletic implements, such as bicycles, which will appeal to the public as a healthy form of competitive amusement, and to associate with bicycles efficient mechanical appliances which will insure accurately 25 an indication of the relative proficiency of the participants, thereby eliminating any element of chance or of unfair indications, such as result from inefficient 30 mechanism which has been employed under somewhat similar conditions in other amusement appliances. More particularly, the invention is concerned with the provision of a single clutch, operable by the attendant, to 35 connect the several bicycles with their respective driven indicating mechanisms so as to insure a fair start of the race. A further object is to provide an improved transmission 40 between the sprocket of each bicycle and its driven indicating means so that such indicating means is driven at all times in exact 45 accordance with the speed of propulsion of the bicycle sprocket. Still another object is to mount within sight of all of the participants 50 miniature figures which travel along a track in exact accordance with the speed of propulsion of the sprockets of the respective bicycles and indicate to the participants at all times during the race their 55 relative proficiency. Another object of the

invention is to provide visual electrical indicating means controlled by the said miniature figures to indicate the real winner at the conclusion of the race. A further object is to associate with the miniature figures 60 and the track over which they move a barrier, operable by the attendant at the time of operation of the clutch for the transmission, to insure a fair get-away of the several figures at the commencement of the race and 65 to mark their relative positions at the conclusion of the race. The invention will be described in greater detail hereinafter in connection with the detailed description of the illustrated embodiment in the drawings, 70 in which drawings—

Figure 1 is a view in plan of the improved device showing the relation of the bicycles to the track over which the miniature figures move.

Fig. 2 is a view partly in side elevation and partly in section of the device shown in Fig. 1.

Fig. 3 is a fragmentary view in side elevation and on a somewhat larger scale of 80 one of the miniature figures which is movable over the track.

Fig. 4 is a view in front elevation of the figure shown in Fig. 3, the front wheel of the miniature bicycle being removed.

Fig. 5 is a fragmentary view in side elevation and on a somewhat larger scale showing the transmission mechanism between one of the bicycles and the driven chain which carries the miniature figure on 90 the track.

Fig. 6 is a fragmentary detail view in elevation showing the relation of the driving chain to one of the miniature figures on the track and the electrical devices for announcing the winner.

Fig. 7 is a detail view partly in elevation and partly in section showing the improved clutch for the transmission mechanism between one of the bicycles and its driven 100 mechanism.

In accordance with the invention, two or more bicycle frames *a* are mounted on a stationary base, the sprockets *a'* and *b* of two such bicycles being indicated in Fig. 105 1 with their associated pedals *a²*, *b²* and sprocket chains *a³*, *b³*. Since the transmission mechanism between the sprocket chain *a³*, *b³*, etc., of each of the bicycles is the same, it will be sufficient for the purpose 110

of this specification to describe the transmission and associated elements of only one such transmission. As shown particularly in Figs. 5 and 7, the sprocket chain a^3 drives 5 a sprocket a^4 which is idle on a shaft c journaled in suitable standards d mounted in front of the bicycle a . On the shaft c is slidingly mounted a clutch sleeve e on the face of which are carried clutch pins 10 e' adapted to pass through holes f in a guide disk f' fastened to the shaft c . When the clutch sleeve e is slid to the left, as viewed in Fig. 7, the pins e' enter holes a^5 formed in the hub of the sprocket a^4 thereby coupling the sprocket to the shaft c . The clutch sleeve e is engaged operatively by an arm g which is carried by a sleeve g' slidably mounted on a shaft h journaled in the standards d . The shaft h has secured there- 15 to a collar h' which is connected yieldingly through a spring h^2 with the sleeve g' . The shaft h also has secured thereto a collar h^3 which is connected through a link h^4 to a clutch lever h^5 pivoted, as at h^6 , to one of 20 the standards d . The point of attachment h^7 of the link h^4 to the lever h^5 is at one side of the fulcrum h^6 of the lever; so that the link is off center with relation to this fulcrum in either extreme position of the 25 lever. A stop h^8 is carried on the lever so as to engage the link h^4 and limit the movement of the lever when the clutch is thrown into engagement. By this construction, as will be evident, the clutch is automatically 30 locked by the off center engagement in both its operative and inoperative positions. The shaft h , it should be noted, may be extended transversely across the entire series of bicycles, so as to operate clutch members 35 for each of the respective transmissions in the precise manner described with relation to the bicycle a . In this way, when the attendant throws the clutch lever h^5 all of the sprocket chains a^3 , b^2 , etc., are connected 40 operatively with the respective transmissions of the various bicycles.

On the shaft c is secured a spiral gear i which meshes with a spiral gear k on a shaft k' , this shaft being operatively geared 45 through a spiral gear k^2 thereon with a vertically disposed driven shaft k^3 . The sprocket chains b^2 , etc., of each of the other bicycles are operatively connected by corresponding elements to other vertically disposed drive shafts b^3 , etc.

In front of the series of bicycles is supported a track l , as by columns l' , and this track has cut therein slots l^2 , l^3 , corresponding in number to the number of bicycles in 50 the series. The shaft k^3 driven from the sprocket chain a^3 has a bearing k^4 formed in the under surface of the track l and carries adjacent its upper end a sprocket wheel k^5 which engages a chain m supported on 55 idlers m' and adapted to travel directly be-

neth the slot l^3 . The sprocket k^5 , it will be noticed, bears on the inside of the chain thereby bringing the maximum number of sprocket teeth in engagement with the links at all times. While the track l is shown as 70 of elliptical form and the slots l^2 , l^3 etc. are of a corresponding outline, it is to be understood that a straight track with straight slots might be employed, in which case some of the provisions made especially by reason 75 of the curvature of the track and slots would be found unnecessary. The chain m carries a plate m^2 which extends up through the slot l^3 and supports above the track a miniature bicycle n on which is a miniature rider n' , 80 one of the wheels n^2 of this miniature bicycle being in frictional engagement with the surface of the track and adapted to drive a sprocket chain n^3 and through it move the legs n^4 of the miniature rider in such manner as to simulate the usual motions of a 85 bicycle rider.

From the description given, it will be evident that the miniature bicycle n on the track l will travel at a speed which is proportionate to the speed of travel of the sprocket chain a^3 and that this speed will depend entirely upon the proficiency of the rider on the bicycle a . In like manner the driven shaft b^3 derives its movement from 90 the sprocket chain b^2 of another bicycle and through the engagement of a sprocket wheel b^4 on this shaft with a second chain o immediately beneath the slot l^2 , a second miniature bicycle o' above the track l is propelled in accordance with the proficiency of 95 the rider on the bicycle having the sprocket chain b^2 . By reason of the different radii of the slots l^2 , l^3 , compensation for the different linear distances which the miniature bicycles n , o' travel around the track is made up by making the sprocket wheel b , b' on the different bicycles of different teeth ratio. In this way, although the miniature bicycle 100 o' has to travel a greater linear distance than the bicycle n , the rider on the bicycle a has the advantage of the other rider by having 105 a larger gear ratio on his driving sprocket, thereby making the miniature riders travel at a speed in direct proportion to the proficiency of the riders.

Above the track l and extending transversely to the slots l^2 , l^3 is mounted a barrier p , movable vertically along guide standards p' and supported by a cord p^2 which extends 110 over pulleys p^3 and is connected to a foot pedal p^4 by depression of which the attendant may raise the barrier p above the level of the miniature riders n' , o' . At the commencement of the race the miniature riders 115 are brought along the slots up to this barrier p and placed on line with one another, so that the raising of the barrier will leave the miniature riders free to be moved and a fair and simultaneous get-away is insured. 120

- After the miniature riders have passed the barrier, the attendant may take his foot off the pedal p^4 , whereupon the barrier will drop by gravity into position across the slots 5 l^2, l^3 . At the end of the race the relative positions of the miniature riders will be accurately indicated to the participants since the barrier serves as a finish line and a marker.
- 10 In each of the slots l^2, l^3 and at a little distance from the barrier p there are mounted pairs of opposed spring terminals q, q' , respectively, which are in electrical circuit with a display frame r having numbers corresponding to the numbers of the various bicycles in the series. When the plate m^2 , say, carrying the miniature bicycle n , comes into contact with the pair of terminals q in the slot l^2 the corresponding number for 15 that bicycle will be flashed in the display frame r so as to indicate the number of the winning machine. In like manner, if any one of the other miniature bicycles first makes contact with its terminals the corresponding number will be flashed. When 20 two or more finish simultaneously, the numbers will be flashed simultaneously.
- 25 In making use of the apparatus the sprocket chain a^3, b^2 of the various bicycles will be manipulated to bring the respective miniature figures n, o' into line adjacent the barrier p and the clutches of all of the transmissions will be simultaneously released by manipulation of the clutch lever h^5 in the 30 manner described. The attendant will then raise the barrier p by depressing the foot lever p^4 and at the same time throw the clutch lever h^5 to engage simultaneously all of the clutches of the several transmissions.
- 35 The riders on the various bicycles will then pedal and the miniature figure connected to the machine of each rider will travel over the track at a speed proportionate to the proficiency of the particular rider. At all 40 times the relative positions of the various figures will indicate the relative speeds which the various riders are making and a very keen competitive interest will be maintained at all times. Since the connection between each of the bicycles and the miniature figures is a positive mechanical one, there is no element of chance or unfairness about the 45 conclusion of the race since the best rider will necessarily win. Under some circumstances, it is possible that the pins e' of each of the clutch members will not register exactly with the holes a^5 in the idler sprocket wheels a^4 but will impinge on the metal between the holes. In case there is no rider on 50 the particular bicycle in whose transmission this condition occurs, the yielding connection h^2 between the sleeve g' and collar h' will, nevertheless, permit the clutch shaft h to be slid for the purpose of throwing in 55 the clutch elements of the transmission of the other bicycles. In such a case the clutch sleeve e would not slide but the collar h' would slide with the shaft h relatively to the sleeve g' . In case this condition exists with a rider on a particular bicycle, a slight 60 movement of the pedals would, of course, cause the holes a^5 to register with the pins e' , whereupon the spring h^2 would immediately throw the pins into the holes and clutch the sprocket a^4 to the shaft c . At the 65 conclusion of the race as soon as the winner's number is flashed on the display frame r the attendant will throw the clutch lever h^5 to disengage the transmissions of all of the several bicycles so that the miniature 70 figures on the track will at once stop moving and remain in the relative order of their finish. It will be necessary to disengage the machines at this time also since the barrier p is resting across the slots l^2, l^3 and might 75 be engaged by the miniature figures if they were permitted to continue their travel. As a safeguard against any such possible collision the pairs of electrical terminals q, q' are spaced somewhat from the barrier p so 80 that the winner's number is flashed sometime before the barrier is actually reached.
- 85 Certain modifications in the apparatus might be made without departing from the spirit of the invention. As pointed out before, the track l might be of some other than elliptical shape and where this track and the slots l^2, l^3 are straight, it would become unnecessary to provide a differential 90 gearing ratio between the sprocket b, a' . 100 Again, it is conceivable that where it is desired to propel the miniature figures by the arms instead of by the legs, hand crank might be substituted in place of the pedals b', a' .
- 95 I claim as my invention:
1. In an amusement device, a series of stationary bicycle frames including a sprocket for each, a separate sprocket wheel for each bicycle frame mounted loosely on 110 a shaft and connected operatively to the first named sprockets, respectively, a fixed track, movable devices mounted in proximity to the track to indicate the relative speed of operation of each of the bicycles, transmission mechanism interposed operatively between each of said bicycles and the respective indicating devices, a clutch interposed in the transmission mechanism of each 115 bicycle and including a clutch sleeve fixed on each of said shafts and having pins to engage the second named sprocket, an arm engaging the sleeve for each clutch, a single shaft with which each of said arms is movable, and means to slide said last named 120 shaft to operate all of said sleeves simultaneously.
- 125 2. In an amusement device, a series of bicycle frames including a sprocket for each, a second sprocket for each frame mounted 130

loosely on a shaft and connected operatively to the first named sprocket, a fixed track, movable devices mounted in proximity to the track to indicate the relative speed of operation of each of the bicycles, transmission mechanism interposed operatively between each of said bicycles and the respective indicating devices, a clutch interposed in the transmission mechanism of each 10 bicycle and including a clutch sleeve fixed on each of said shafts and having pins to engage the second named sprocket, an arm engaging each of said sleeves, a second sleeve on which each of said arms is carried, 15 a single shaft on which each of said last named sleeves is loosely mounted, collars fixed on the last named shaft and yielding connections between the respective collars and second named sleeves.

3. In an amusement device, a series of 20 stationary bicycle frames, a fixed track, miniature figures mounted in proximity to the track to indicate the relative speed of operation of each of the bicycles, said track being provided with a slot for each of said 25 figures, an operating chain beneath each slot on which the respective figures are mounted, transmission mechanism for each figure operatively interposed between the chain for 30 said figure and the corresponding bicycle, clutches interposed in each of said transmission mechanisms, a barrier for the figures mounted on the track across the slots and means to raise the barrier.

This specification signed this 3d day of 35 December, 1919.

PHILIP FABER.
